EDGE CONSTRUCTION FOR TABLE TOPS AND THE LIKE

Application filed June 18, 1928. Serial No. 286,094.

This invention relates to a novel edge construction for desk and table tops and the like.

An object of the invention is to provide an edge construction for desk and table tops, consisting of a relatively small number of inexpensively manufactured and readily assembled parts, which will lend a neat and attractive appearance to the desk or table top.

Another object of the invention is to provide an edge construction for desk and table tops, which will be sturdy and rigid, though light in weight.

These and other objects of the invention will become more readily apparent in the course of the following description of the invention, taken in connection with the accompanying drawings, wherein

Fig. 1 is a fragmentary perspective view of one corner of a desk or table top, in which the novel features of the present invention are embodied;

Fig. 2 is a cross-section through the desk or table top, taken on the line 2—2 of Fig. 1; and

Fig. 3 is an exploded view of the various parts shown in Fig. 1.

Referring more particularly to the drawings, the edge construction includes a metal top plate 1 to the upper surface of which is secured, as by cementing or the like, a linoleum cover 2, provided with a beveled edge 3.

A Z-bar 4, comprising a web 5 and legs 6 is secured, as by spot welding, to the lower surface of the top plate 1, near the edges thereof, and the web of this bar is provided at spaced intervals with holes 7 for the reception of screws 8.

A binding strip 9, preferably of brass or bronze, abuts the edges of the top plate 1, and consists of an inturned flange 10, a horizontal web 11, and a depending flange 12. The inturned flange 10 of the binding strip protects and binds the beveled edges 3 of the linoleum cover 2.

A channel retaining member 13 consisting of a web 14 and legs 15 and 16 is provided at spaced intervals with tapped plates 17, which are preferably secured as by welding or the like to the inner face of the web. The tapped holes 18 of these plates are in alignment with the holes 7 in the web of the Z-bar 4.

The various parts are assembled as clearly shown in Fig. 2, the screws 8 serving to retain the channel retaining member 13 in clamping engagement with the binding strip 9.

Having described my invention, what I claim is:

1. In an edge construction for table tops and the like, a top plate, a member secured to the lower surface of said plate, a binding strip abutting the edges of said plate, a retaining member of channel cross-section abutting said binding strip, tapped plates secured to the web of said retaining member, and means extending through said first-named member and into said tapped plates, and serving to retain the binding strip in place.

2. In an edge construction for table tops and the like, a top plate, a member secured to the lower surface of said plate, a binding strip abutting the edges of said plate, a retaining member of channel cross-section abutting said binding strip, tapped plates secured to the web of said retaining member, and screws extending through said first-named member and into said tapped plates, and serving to retain the binding strip in place.

3. In an edge construction for table tops and the like, a top plate, a Z-bar secured to the lower surface of said top plate, a binding strip abutting the edges of said plate, a channel retaining member having tapped plates secured to the web thereof, and means extending through the web of the Z-bar and into the tapped plates, and serving to retain the binding strip in place.

4. In an edge construction for table tops and the like, a top plate, a Z-bar secured to the lower surface of said top plate, a binding strip abutting the edges of said plate, a channel retaining member having tapped plates secured to the web thereof, and screws extending through the web of the Z-bar and into the tapped plates, and serving to retain the binding strip in place.

5. In an edge construction for table tops and the like, a top plate, a member secured to the lower surface of said plate and having a portion spaced inwardly from the marginal edges of said top plate and an outwardly extending portion parallel with and spaced

from said top plate and constituting an abutment, a binding strip abutting the edges of said plate, a retaining member abutting said binding strip and abutment and means securing said retaining member to said first-named member.

6. A structure as defined in claim 5, in which the retaining member is provided with tapped plates rigidly secured thereto, and
10 the means for securing the retaining member to the first-named member comprises headed screws, the heads of which abut the inwardly spaced portion of the first-named member and threaded portions of which extend into the tapped plates.

7. In an edge construction for table tops and the like, a top plate, a member secured to the lower surface of said plate and having a portion spaced inwardly from the marginal
20 edges of said top plate and a portion parallel with and spaced from said top plate and extending outwardly to a point below the marginal edges of said top plate and constituting an abutment, a binding strip abutting
25 the edges of said plate, a retaining member abutting said binding strip and abutment and means securing said retaining member to said first-named member.

8. A structure as defined in claim 7, in
30 which the retaining member is provided with tapped plates rigidly secured thereto, and the means for securing the retaining member to the first-named member comprises headed screws, the heads of which abut the inward-
35 ly spaced portion of the first-named member and the threaded portions of which extend into the tapped plates.

In testimony whereof I affix my signature.
FRED A. SCHMITZ.
